UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

1,378,076.

Specification of Letters Patent. Patented May 17, 1921.

Application filed February 16, 1920. Serial No. 358,885.

To all whom it may concern:

Be it known that I, FRANKLIN R. WHITE, a citizen of the United States, and a resident of Waterbury, in the county of New Haven 5 and State of Connecticut, have made and invented certain new and useful Improvements in Buttons, of which the following is a specification.

My invention relates to buttons, and particularly to that class or type, which are composed of a button proper and a metallic fastener, the two being permanently secured together and to cloth or other material by means of an automatic button attaching machine. This type or class of button has heretofore been entirely composed of metal. It has also been the practice to coat, plate or in other manner finish the surface of the metal, so as to prevent the button from corroding 10 or rusting and in order to harmonize with the cloth or material to which the button is attached. In practice, however, the external finish upon the button wears off and under adverse conditions the button will corrode 15 and rust and in turn mar and destroy the cloth to which it is attached. Further the increasing cost attending the production of buttons formed entirely of metal is a serious disadvantage, and it is accordingly an object 20 of my invention to provide a button of the class described, which is partly composed of metal and partly composed of a light fibrous material, which will not rust or corrode, and is of uniform color throughout.

30 A further object is to provide a button, which can be produced more economically than a button, which is composed entirely of metal and which button will be rugged and durable in use as well as possessing a pleasing and finished appearance.

40 A further object is to provide a button, the body portion of which will not change in color or appearance as it becomes worn or the surface marred or scratched; the coloring extending uniformly through the material of which the button is composed.

45 A further object is to provide a button, which although partially composed of a fibrous non-metallic material, is so constructed that the metallic prong of a fastener may be received therein and headed and permanently anchored thereto, whereby the button will possess all of the rugged characteristics of a button entirely composed

of metal, at the same time will not be subjected to the disadvantages and limitations of an entirely metallic button.

With the foregoing and other objects in view, which will appear as the description proceeds, my invention resides in the novel 60 button, illustrated and described herein, and in the combination and arrangement of parts, and in the details of construction thereof.

The preferred embodiment of my invention is illustrated in the accompanying drawings, wherein:—

Figure 1 is a view in longitudinal vertical section of a button, embodying the characteristic features of my invention.

Fig. 2 is a similar view illustrating the fastener permanently secured in place.

Fig. 3 is a view in vertical longitudinal section of a slightly modified form of button.

Fig. 4 is a top plan view of the button 75 illustrated in Figs. 1 and 2.

Referring specifically to the several views wherein similar reference numerals designate corresponding parts throughout, the button is formed with a fastener A, including the 80 upstanding prong 10, which by the action of a suitable machine is forcibly driven through the cloth or material B, and permanently secured to the body portion C of the button.

The body portion of the button is constructed with the top 11, downwardly projecting hub 12, and the base 13, a suitable opening 14, extending through the latter for the reception of the prong of the fastener 85 therein. In order that the body as thus constructed will be light in weight, of uniform color and texture throughout, I prefer to form it of non-metallic material, which is hard, substantially chemically inert so as not to corrode the material B, to which it is attached, and to this end, use or employ a form 90 of fiber, which has been suitably treated, so that it may be pressed, molded, or in other ways shaped to the desired configuration.

Fitting within the hub of the body is the 100 metallic cup-shaped anchor 15, the bottom wall 16, of which is curved upwardly and perforated so as to form the mouth or throat 17. The anchor is forcibly pressed within the non-metallic hub of the body of the button with the opening or mouth 17 in alignment with the opening 14 of the base, so that as the prong of the tack or fastener is for-

cibly driven through the cloth or material B, it will extend within the metallic anchor and be headed against the upper wall thereof, the mouth 17 preventing the withdrawal 5 of the fastener.

In those instances where it is desirable to provide the top of the button with a suitable inscription or monogram or whenever desired, a metallic cap 18, as illustrated in 10 Fig. 3, may be secured to the top of the button and extends there across, there being a suitable flange 19, projecting down over the body of the button and engaging the same.

I have found that with a button as thus 15 constructed not only is it light in weight, and more economical to produce than a similar button made of metal, but being of uniform color throughout, retains the desired appearance although the surface become 20 worn, marred or scarred, and further will

not corrode or mar the cloth to which it is attached.

Having thus described my invention, what I claim is:—

A button of the class described for use with 25 automatic button attaching machines, comprising a body portion including a top, a hub, and perforated base, formed of non-metallic material, of uniform color throughout, and a metallic cup-shaped anchor 30 secured within said hub, having an open ended cavity in alignment with the opening in said base.

Signed at Waterbury, in the county of 35 New Haven, and State of Connecticut, this 2nd day of Feb., A. D. 1920.

FRANKLIN R. WHITE.
